UNITED STATES PATENT OFFICE.

MANSFIELD C. CRAWLEY, OF LOS ANGELES, CALIFORNIA, ASSIGNOR TO ADDOGRAPH COMPANY, A CORPORATION OF CALIFORNIA.

TYPE-WRITER AND COMPUTING MACHINE.

1,273,828.

Specification of Letters Patent. Patented July 30, 1918.

Application filed October 28, 1911. Serial No. 657,311.

To all whom it may concern:

Be it known that I, MANSFIELD C. CRAWLEY, a citizen of the United States, residing at Los Angeles, in the county of Los Angeles, and State of California, have invented new and useful Improvements in Type-Writer and Computing Machines, of which the following is a specification.

This invention relates to a combination typewriter and computing machine.

It is the object of this invention to provide a combination typewriter and computing machine which is adapted to be used separately either as a typewriter or as a computer, and which is so constructed that both the typewriter and computer functions may be performed at the same time, thus producing a machine by means of which itemized statements of various kinds may be prepared and columns of figures added by the computer to obtain a total. A further object is to provide means by which the type and digit bars are operated to obtain a uniform and positive impression and to be returned to normal by motor power, thus producing a machine which is capable of being operated at a very high speed.

Another important object of this invention, resulting from spring and power actuated type and digit bars, is that the key-bars, the functions of which are to merely release the type or digit bars, having slight resistance, may be depressed with ease. Other objects will become apparent in the following description of the invention.

The invention consists of the parts, and the combination and construction of parts as will be hereinafter more fully described and claimed, having reference to the accompanying drawings, in which—

Figure 1 is a transverse section of the invention, partly in elevation.

Fig. 2 is a detail of the type and digit-bar operating mechanism.

Fig. 3 is a detail in perspective of the end portion of the type and digit bar actuating arm.

Figs. 4 and 5 are plan views of rack attachments which are applied to the paper carriage when the computer is to be employed.

Fig. 6 is a section on the line U—U of Fig. 7.

Fig. 7 is a plan view on the line V—V of Fig. 1, showing the computer selective mechanism. 55

Fig. 8 is an enlarged section on the line W—W of Fig. 7, showing the computer operating mechanism in elevation with parts broken away. 60

Fig. 9 is a detail section on the line X—X of Fig. 8.

Fig. 10 is an enlarged section on the line Y—Y of Fig. 7, showing the computer reversing mechanism in elevation. 65

Fig. 11 is an enlarged section on the line Z—Z of Fig. 7.

Fig. 12 is a detail in plan of the operative mechanism for returning the type bar actuator to normal. 70

Fig. 13 is a front elevation of the machine with parts broken away.

Fig. 14 is a detail and side elevation of the computing mechanism.

Fig. 15 is a front elevation of the same. 75

Fig. 16 is a detail in elevation of the traveling pinion.

Fig. 17 is a detail perspective view of the operating levers and equalizing springs employed in the computing mechanism. 80

Fig. 18, Sheet 2, is a detail side elevation of the type actuator restoring mechanism.

In the drawings, A represents a key bar of the typewriting mechanism, which is provided with the usual depressing button A', 85 and is fulcrumed at 2.

The inner end of the key bar A is pivotally connected to a vertically disposed operating arm 3, the upper end of which is guided in, and adapted to pass through, a slot 90 formed in a stationary segment 4, mounted on the frame 5 of the machine. A spring 6 mounted on the operating arm 3, normally retains the latter in its lowermost position.

There are as many key bars A and operating arms 3 provided, as just described, as there are keys or buttons A' on the typewriting portion of the machine. 95

Disposed above the upper end of the operating arm 3, above the segment 4, is a type bar actuating arm 7, the lower end of which extends downward at 8 and is normally held in contact with the segment 4 by means of a spring 9.

The upper end of the arm 7 is pivoted to 105 the short arm of the type bar 10 in close prox-

imity to the fulcrum point 11 of the latter. The lower end of the arm 7 is also provided with a hooked portion 12 which is adapted to be engaged by a reciprocating segmental actuating bar 13, when the lower end 8 of the arm 7 is moved upward by operating the arm 3, as later described and as shown in Fig. 2.

The actuating bar 13 is carried by means of links 14 from outwardly extending brackets 15 mounted on a rigid portion of the frame 5. A stiff spring 16 normally bears against the back of one or more of the links 14 adjacent the brackets 15 and tends to move and retain the actuating bar 13 in its forwardmost position, as indicated in dotted lines in Fig. 2.

Means are provided for normally retaining the actuating bar 13 in its rearward position in opposition to the tension of the spring 16, which means is adapted to be operated by the depression of a key A to release the actuating bar 13 and permit its being carried forward by the spring 16. The above-mentioned means are constructed as follows: Pivotedly mounted on a bracket 17 on the actuating bar 13 is a link 18, which extends rearward of the bar 13 and connects with a crank 19 loosely mounted on a shaft 20. The outer end of the crank 19 carries a pawl 21 which is adapted to be engaged with, and disengaged from, a ratchet 22 rigidly mounted on the shaft 19. The pawl 21 is held out of contact with the ratchet 22 when the bar 13 is in its rearwardmost position by means of a stationary cam 23 mounted on a hanger on the frame 5, on which cam the outer end of the pawl 21 is designed to ride, as later described.

When the pawl 21 is disengaged from the ratchet 22, the crank 19 is free to move or be held stationary, independent of the revoluble shaft 20 on which it is mounted and which shaft is adapted to be constantly rotated through gears 24 and 25, by means of a motor 26.

It will be seen that, by obstructing the crank 19 at a point corresponding to the position it will assume when the actuating bar 13, carrying the link 18, is in its rearwardmost position, the actuating bar 13 will be prevented from being moved forward, and that by relieving the crank 19 at this point the spring 16 will carry the bar 13 forward with considerable velocity.

The mechanism for locking the crank 19 consists of a depending pawl or dog 27, pivoted at its upper end to the frame 5, the crank engaging member 27' of which is normally disposed in the path of travel of the outer end of the crank 19 in such manner as to prevent further movement of the latter when it reaches this point, as later described. The dog 27 is normally retained in its crank engaging position, by means of a

spring actuated bell-crank lever 28, which is pivoted at 29 to a fixed member on the frame 5, and has a projection 28' on its lower end which bears against the back of an extended portion of the dog 27. A spring 30, is wound around a stud on the lever 28 and bears between a rigid pin and the lever 28 in such manner as to exert an inward pressure on the lower end of the lever 28.

The device for releasing the dog 27 from engagement with the crank 19, comprises a link 31, one end of which is provided with a slot into which a pin 32 on the dog 27 extends, and the other end of which engages a curved releasing bar 33 which is located between the segment 4 and the actuator bar 13 in contact with the upper face of the downwardly extending portion 8 on each of the type-bar actuating-arms 7. The bar 33 is here shown as extending downward at each end and pivoted at 34 at a point against the key bars A, but any other manner of mounting the bar 33 by which it can have a certain transverse reciprocal or oscillatory movement, may be employed if desired.

In operating the typewriter mechanism just described, a button A' is depressed, thereby rocking the key-bar A on its pivotal mountings 2 so as to move the operating arm 3 upward through the guide slot in the stationary segment 4. This brings the upper end of the operating arm 3 into contact with the downwardly inclined end 8 of the arm 7, thus moving the latter upward on its pivotal mounting 7' so as to dispose the hook 12 in front of the reciprocating actuating-bar 13, as shown in Fig. 2. As the inclined portion 8 of the arm 7 moves upward, the bar 33 is moved backward by reason of the inclined portion 8 bearing against the bar at a point 45° from its center, thus acting as a wedge to move the bar 33 backward on its pivotal mountings 34.

The rearward movement of the bar 33 carries the slotted link 31 rearward therewith, so as to throw the projection 27' on the lower end of the dog 27 out of engagement with the crank 19, which permits the latter to rotate on the shaft 20 and thus release the bar 13.

The bar 13 is then caused to move forward by means of the tension of the springs 16 bearing against the links 14, the links 18 pulling upon the loose crank 19 to carry the pawl 21 over the cam surface 23, the cam 23 permitting the pawl 21 to travel free from engagement with the ratchet 22 while the bar 13 is moving in a forward direction.

The springs 16 act on the link 14 to impel the actuating bar 13 forward with considerable velocity, the forward movement of the bar 13 acting to impel the type bar 10 upward against the platen roll 35 through the arm 7 which has been previously disposed

in front of the movable bar 13, as before described. A uniform impact of all the type in the machine on the platen roll is insured for the reason that one spring or set 5 of springs 16 control the forward movement of the actuator-bar 13, which bar operates on all the type bars.

The moment the impression is made by the type bar 10, the spring 9 returns it and 10 the arm 7 to the normal position shown in Fig. 1. In the meantime, the pawl 21 has been carried clear of the cam 23 by means of the link 18 and crank 19, which are carried forward by the actuating bar 13. The 15 moment the pawl 21 is released from the cam 23 a spring 21', on the pawl throws it into engagement with the rotating ratchet wheel 22 on the shaft 20, so that as the ratchet revolves the crank 19 will be carried there- 20 with, thus pulling upon the link 18 to return the bar 13 back to its normal position, in opposition to the spring 16 where it is retained by the dog 27 reengaging the crank 19.

25 The moment the crank 19 is engaged by the dog 27, the heel of the pawl 22 strikes the cam 23 which action rocks the pawl 27 and releases it from engagement with the ratchet 22, in which released position it is 30 retained by the cam 23 until the crank 19 is again released from the dog 27 and is again moved forward by the springs 16, as before described.

The moment the bar 13 starts back to its 35 rearward position it releases the hook 12 on the arm 7, thereby allowing the spring 9 to pull the arm 7 downward until the lower end of the inclined portion 8 comes in contact with the slotted segment 4, the lower 40 end 8 of the arm 7 moving rearward into contact with the edge of the actuating arm 3 extending through the segment 4, so as to move the latter rearward against the tension of the spring 6, as shown in dotted lines in 45 Fig. 2, the spring 9 at the same time restoring the type bar 10 to normal. As this occurs, the spring 6 returns the arm 3 and key-bar A to normal, the upper end of the arm 3 passing beneath the lower end of the projection 8 in position for another operation, and the releasing bar 33 assuming its former 50 position over the inclined portion 8 of the arm 7.

The platen roll 35 is mounted on a reciprocating carriage 36, which is adapted to travel back and forth on a track-way 37, as is common in typewriter construction. As the operation of the platen roller 35 and the carriage 36 forms no part of the present invention, the mechanism for operating the same is not here shown.

In the computing machine embodied in this invention, shown in Fig. 6, I employ a series of digit bars 50 corresponding to the

type-bars 10 in the typewriting machine. 65 The digit bars 50 are mounted on the frame 5 with the type bars 10 and are designed to be actuated by the reciprocal bar 13 from the motor 26 in the same manner as described in relation to the type bars 10. 70

The usual series of numeral keys are provided on the key-board of the machine, indicated by the button B, Fig. 1, for the purpose of printing the numeral characters, and also for operating the computing device, the 75 buttons B in this case being ten in number, and marked with the digits 0 to 9, inclusive. Each button B is mounted on a key-bar B', which is pivoted at 2 and is provided with an operating arm 3 extending upward 80 through a slot in the stationary segment 4 in contact with the inclined end 8 of the arm 7 which is pivotally mounted on the under end of each digit bar 50, the members 3, 7 and 8 corresponding to the same members employed with the type bars 10.

When it is desired to operate the computing machine, either in connection with or independent of the typewriting mechanism, it is necessary to attach a toothed rack 52, 90 such as shown in Figs. 4 and 5, to the platen-carrying carriage 36, as shown in Fig. 1. This rack 52 is designed to engage a pinion 53 mounted on the upper end of a shaft 54 disposed in the rear, and independent of the 95 carriage 36 and mounted in suitable bearings on the frame 5.

The lower end of the shaft 54 is provided with a drum 55, around which the ends of a cable 56 are wound in opposite directions, 100 one portion of the cable 56 leaving the drum 55 passing around suitable direction pulleys 57-58 mounted on the frame of the machine and leading to one side of a slideable carriage 59 mounted on a guide shaft 60, as shown in 105 Fig. 15. The other section of the cable 56 passes around direction pulleys, not shown, opposite the pulleys 57-58 and corresponding thereto, and connects with the other side of the carriage 59.

It will be seen that as the carriage 36 is moved backward and forward longitudinally on the track-way 37, to carry the rack 52 across the pinion 53 in either direction, the pinion 53 will be caused to revolve and 115 thereby wind one section of the cable 56 on the drum 55, while the other section of the cable unwinds, thus causing the carriage 59 to be moved along the guide shaft 60 simultaneous with the movement of the carriage 120 36.

The drum 55 is so proportioned with relation to the diameter of the pinion 53 that the carriage 59 will be moved approximately twice the distance traveled by the carriage 125 36, as the latter shifts its positions from one point to another at each depression of a button B, or otherwise, the shifting of the car-

riage 36 being accomplished in any desired manner, either by hand or mechanism not necessary to be here shown.

A revolving shaft 61 mounted on suitable bearings on the frame 5 is disposed beneath the guide shaft 60 in vertical alinement therewith.

A ten-toothed computer-actuating gear 62 is key-seated on an enlarged portion of the shaft 61, as shown in Figs. 14 and 15, so as to be slideable lengthwise thereon and turnable therewith. Downwardly projecting members on the carriage 59 extend around the shaft 61 on each side of the gear 62 so that when the carriage 59 is moved from side to side on the guide-shaft 60 the gear 62 will be carried therewith.

Mounted on the shaft 61 is a gear 63, which is in constant mesh with a pair of gears 64—65, revolubly mounted on a rocking-lever 66 mounted upon the shaft 61 and adapted to be rocked thereon. The gear 65 is in constant mesh with a gear 67 also mounted on the rocking-lever 66; the gears 64 and 67 being positioned on the lever 66 in such manner as to be alternately thrown in and out of engagement with a gear 68 revolubly mounted, as later described, on a stud 69 fixed on the frame 5, the purpose of the gears 64 and 65—66 being to provide means for driving the shaft 61 in either direction from the gear 68, which gear is designed to rotate in but one direction.

The mechanism for rocking the lever 66 consists of a link 70 connected to the lower end of the lever and to a bell-crank lever 71 mounted on the frame 5, which bell-crank lever 71 connects with a second bell-crank lever 71' adapted to be actuated by one of the key-bars 71.

The gear 64 is normally retained in mesh with the gear 68 by means of a spring 72 which exerts an upward pull on the outer end of the key-bar A and when it is desired to throw the gear 64 out of engagement with the gear 68, and to throw the gear 67 into engagement therewith, the button 73 on the key-bar 71 is depressed and retained in its lower position, which action rocks the lower end of the lever 66 inwardly and thus performs the required action.

Formed on the face of the gear 68 is a ratchet 74 which is adapted to be engaged by a spring pressed pawl 75 mounted on an arm 76 formed on the outer end of a sleeve 77. The sleeve is supported and revoluble upon the stud 69, and the gear 68 is revolubly mounted thereon so as to rotate independent thereof. The sleeve 77 is adapted to be rotated by means of a gear 78 which is rigidly mounted on the sleeve and is in constant mesh with a reciprocal toothed rack 79 mounted and guided in suitable bearings on the frame 5, which rack is adapted to be moved lengthwise in one direction, in strokes

of various lengths on the forward movement of the actuating bar 13, as will presently be described, so as to rotate the gears 78 and 68, and thereby revolve the shaft 61 a predetermined distance. The rack 79 is connected to the lower end of a lever 80 through a link 81, and the lever 80, fulcrumed at 82, is connected to the actuating bar 13 by means of a connecting rod 83. The rod 83 is slotted at 84 through which slot a pin 85 mounted on a bracket 86 carried by the bar 13 extends.

A spring 87 exerts a pull upon the lever 80 in such direction as to normally retain the inner end of the slot 84 in contact with the pin 85 on the bar 13, and is so arranged that when the latter moves forward, the rod 83 will be moved forward therewith by the action of the spring 87 rocking the lever 80 on its bearings 82; the slot 85 permitting a continued forward movement of the actuating bar 13 after the rod 83 has reached the limit of its forward movement, or when the rod 83 is held stationary, as later described. The spring 87 thus acts to move the rack 79 in a backward direction, which rotates the gear 78, sleeve 77 and arm 76 to cause the pawl 75 to ride over the ratchet 74.

The rack 79 is normally retained in its forwardmost position in opposition to the spring 87 by means of a rocking arm 88 pivoted at 89, the outer end of which arm extends in the path of a laterally disposed projection or pin 90, formed on a downwardly extending member 91 on the rear end of the toothed rack 79. The arm 88 is normally retained in the path of the projection 90 on the rack 79 by means of a spring 92 which exerts an upward tension on the arm 88.

The arm 88 is designed to be depressed so as to move it from in front of the projection 90 on the rack 79 and thereby admit of the latter being moved backward by the action of the spring 87. This is accomplished by means of the operation of any one of a series of selector-bars 93, which selector-bars are pivotally mounted on a rod 94, as particularly shown in Figs. 6 and 7. The bars 93 are arranged side by side with their outer ends extending over a horizontal member 95 carried by the rocking arm 88, and each bar has its inner end normally resting upon a key-bar B', of the numerical series, as shown in Fig. 6; the upward pressure of the arm 88 retaining the bars 93 in this position. The selector-bars 93 are designed to be operated separately and are provided for the double purpose of releasing the rack 79 and at the same time limit the rearward movement of the latter when it is actuated by the spring 87. The operation of a selector-bar 93 is accomplished by depressing a button B which rocks the inner end of the key-bar B' corresponding thereto, in an upward direction, which in turn rocks the se-

lector-bar 93 on the rod 94, so as to cause its outer end to move in a downward direction. The outer end of the selector-bar 93 depresses the rocking arm 88 so as to move it from in front of the projection 90 on the rack 79 to allow the spring 87 to move the latter backward. The actuator 13 is caused to move in a forward direction by the springs 16 and connected with the driving mechanism 10 of the motor 26 as before described, which operation is occasioned by the actuation of the key B'. The pin 85 on the bracket 86 on the actuator 13 being arranged adjacent to the outer end of the slot 84 permits the spring 87 to rock the lever 80 and thereby move the rack 79 in a rearward direction. The rearward movement of the rack 79 by the spring 87 is arrested by means of the outer end of the depressed selector-bar 93 extending into the path of travel of the projection 90 on the rack 79; the projection 90 passing below the outer ends of the unactuated selector-bars 93. The rack 79 being moved backward, the extent of the movement governed by the selector-bar 93 causes the pawl 75 to engage with the ratchet 74 in such manner that when the actuator 13 returns on its backward stroke, which rocks the lever 80 to restore the rack 79 to its normal position, the pawl 75 will operate to rotate the gear 68 which in turn will rotate the shaft 61 through either of the gears 64 or 67, as before described. The moment the projection 90 on the rack 79 reaches its normal position the spring 92 restores the arm 88 in front thereof and at the same time returns the selector-bar 93 to its normal position.

Means are provided for preventing the continued rotation of the shaft 61 after the toothed rack 79 has come to a stop, which means is here shown as consisting of a pawl 96 mounted on the frame 5, and which is thrown into engagement with a square toothed ratchet 97 on the shaft 61 by means of a projection 98 on the rack 79 which engages the pawl 96 when the rack 79 is in its forwardmost position in such manner as to rock the pawl, which is in the form of a lever, and throw it into engagement with the ratchet 97, as shown in Fig. 8.

Mounted on standards 100 is a shaft 101, which is disposed parallel to and a short distance below and in front of the shaft 61. Loosely mounted on the shaft 101 is a series of spaced computing disks 102, the peripheries of which are notched to form teeth which are designed to mesh with the teeth of the gear 62, the teeth on each disk 102 corresponding in number to the teeth on the gear 62. The outer face of the teeth on each disk 102 is provided with reading or indicating numbers, ranging consecutively from 0 to 9, inclusive, and the disks 102 are so arranged with relation to each other that

the numbered teeth, one on each disk, are in alignment with the teeth of the adjacent disk.

The alignment of the teeth of the disks 102 is obtained by means of a series of rollers 103, on spring-actuated arms 104, swivelly mounted on a shaft 104' supported by the standards 100, a roller 103 being provided for each disk 102 and so disposed as to normally engage a notch on its respective disk, as shown in Fig. 14.

The notches and teeth on the disks 102 being aligned, it will be seen that the gear 62 can be moved successively from left to right into engagement with any one of the computing disks 102, or it can be moved from right to left with the engaging tooth of the gear 62 passing freely through the aligned notches in the disks 102.

There are as many of these disks 102 as there are denominations or places to be employed, and the number may be as extensive as desired. In this case, six places are shown, which are sufficient for ordinary purposes, there being one disk to indicate units, one for tens, another for hundreds, and so on up to hundreds of thousands, the unit disk being arranged at the extreme right, as shown in Fig. 15, and the tens, hundreds, thousands, etc., disposed in consecutive order to the left thereof in the usual mathematical arrangement. These disks 102 are for the purpose of indicating the arithmetical results of addition or subtraction as obtained in the operation of the computing portion of this invention, which operation will now be described.

A rack 52 being mounted on the platen-carrying carriage 36, in a position on the carriage corresponding to the position in which the printed numerals are to be located on the paper, the carriage 36 is moved into a position where the first tooth of the rack 52 will engage the pinion 53, by means of a space-key, or by hand, in the usual manner.

Assuming that it is desired to write a number of six places, such for instance, as 123,456, the button B representing the number 1 is first depressed. The key or bar B' corresponding thereto is thereby rocked on its pivotal bearing 2 so as to raise its inner end to move the operating arm 3 which actuates the arm 7 and the digit bar 50 to imprint the numeral 1 on the platen in the sixth position. The digit bar 50 is operated by the operating arm 3 in the same manner as the type bar 10, as before described in relation to the type-writing mechanism.

As the inner end of the bar B' moves upward, it operates a selector bar 93 corresponding thereto so as to rock this bar 93 on its pivotal mounting 94 to throw its outer end into the path of the projection 139.

90 on the rack 79, as before described. This is done an instant prior to the forward movement of the actuating bar 13 which now takes place.

5 The forward movement of the rack 79 now occurs on the return of the bar 13 which is occasioned by the motor 26, and causes the one tooth in the rack 79 to operate the gear 78 the length of one tooth, which, in turn, 10 operates the gear 68 the same distance, so as to rotate the shaft 61 and cause the gear 62 to turn the recording or computing disk 102 one notch, or from the 0 to 1 position, the pinion 62 previously being moved into 15 engagement with the first recording disk 102 by the movement of the carriage 36. The forward movement of the rack 79 also acts to throw the locking pawl 96 into engagement with the ratchet 97 to insure the shaft 20 61 and gear 62 coming to a stop in the proper position.

The return of the bar 13, by means of the motor 26 and its connecting mechanism, as before described, carries the lever 80 rearward in opposition to the spring 87 and returns the rack 79 to normal.

When the computing mechanism is again in position for another operation, and the gear 62 moved into engagement with the 25 second disk 102 by the shifting of the carriage 36, the key marked with the number 2, is depressed so as to actuate the second selector-bar 93 in the series, which will permit the rack 79 to move back sufficiently 30 far to rotate the gears 78-68-64-63 and 35 62 a distance of two teeth so as to rotate the second recording disk 102 two notches, or into the 2-position, disposing the numeral 2 in line with the exposed numeral 1 on 40 the previously operated disk.

In this manner the operator proceeds, until the desired number, in this case 123,456 will be imprinted on a sheet on the platen 35 and the corresponding numbers exposed 45 or indicated on the disks 102 through a reading slot in the casing 5, not shown. This being accomplished, the platen 35 is turned into position to receive the next line of numbers which are to be added to the numbers just written.

The gear 62 is then shifted into engagement with the disk 102, which exposes the number or place to which the next number is to be added, and the button B carrying 55 that number is depressed to rotate the selected disk as many numerical points as contained in the selected number. For illustration, assume it is desired to add the numeral 3 to the numeral 6, previously printed 60 in the units column on the platen and exposed on the unit disk 102 of the computer—the carriage 36 being shifted into a position to cause the digit bar to register an imprint on the platen in the units column 65 below the previously printed 6, the gear 62

becomes positioned to operate the unit disk 102. The 3-button B being depressed, the numeral 3 is printed on the platen and the indicating disk 102 is caused to move three points so as to expose the numeral 9 where 70 the 6 formerly stood, the numeral 9 representing the sum of 6 plus 3. It is obvious that the operation just described would be the same on any one of the disks 102, and that each disk will be moved in accordance 75 with the points denoted by the operating button B, ranging from one to ten, a number being exposed after each operation of a disk 102 corresponding to the sum of the number on the button depressed plus the number previously exposed, a carrying mechanism about to be described being provided for the purpose of carrying the tens from one indicating disk to the next.

In this manner, the operation of adding a 80 column of figures may be carried on indefinitely, being limited in arithmetical places only by the number of recording disks 102 employed. In this case, six disks are shown, from which it will be readily seen 85 that the mechanism here disclosed is limited to a capacity of 999,999.

The operation just described is not confined to addition, the same mechanism being employed, however, for subtraction, which, 90 being reverse to addition, necessitates the reverse rotation of the accumulation or recording disks 102. This is accomplished by depressing the key 73 so as to operate the rocking lever 66 and throw the gear 67 into 95 engagement with the gear 68, which, when rotated will actuate the gear 63, shaft 61 and gear 62, as before described, only in a reverse direction.

The carrying mechanism before mentioned is constructed and operated as follows:

Pivotedally mounted on the shaft 105 supported on the standards 100 is a series of bell-crank levers 106, one of these levers being disposed beneath each indicating disk 102, excepting the unit disk. Each lever 106 carries a trip lever 107, which is pivoted at 108 near the outer end of the long 110 arm of the bell-crank lever 106. Each trip 115 lever 107 normally extends in a vertical direction with its upper end projecting into the space between the disks 102 in the path of travel of the pin 108' mounted on the side 120 face of the disk at the right thereof, as shown in Fig. 14.

A duplex plate spring 109 mounted on the bell-crank 106 acts to normally retain the trip lever 107 in its vertical position, a pin 110 on the lever 107 extending between the two leaves of the spring 109 against which the lower leaf of the spring bears in an upward direction and the upper leaf bears in a downward direction. A pin 111 on the bell-crank 106 is disposed between the upper 125

and lower leaves of the spring 109 to equalize the tension of the spring leaves so as to centralize the pin 110 to maintain the lever 107 in its vertical position.

5 An offset or shoulder 112 is formed on the upper end of each trip lever 107 at a point just out of contact with the under side of the disk 102 thereabove, the purpose of which will be made apparent hereinafter. A 10 hook 113 on the lower end of each trip lever 107 engages a keeper 114 when the bell-crank 106 is moved to its lowermost position with the lever 107 in its vertical position, the hook 113 acting to retain the long 15 arm of the bell-crank 106 in its lowermost position in opposition to a spring 115 disposed between the lower end of the short arm of the lever and a fixed shaft 116 on the standard 100.

20 The function of the spring 115 is to rock the bell-crank lever 106 to move the long arm thereof in an upward direction when the hook 113 on the lever 107 is disengaged from the keeper 114.

25 The pins 108' on the disks 102 are so disposed as to extend alongside the lever 107 on the right-hand side thereof, as shown in Fig. 14, so that when the disks 102 are rotated counter-clockwise from the cipher position to the 9-position in performing the process of addition, as before described, the disk will rotate without operating the lever 107, that is, the disk 102 may be moved to expose the consecutive ordinals 0 to 9, inclusive, without affecting the lever 107.

When a disk 102 is rotated counter-clockwise from the 0 to the 9-position, the pin 108' thereon will be disposed adjacent the left-hand side of the lever 107, as indicated in 40 dotted lines in Fig. 14, so that a continued rotation of the disk will cause the pin to engage the upper end of the corresponding lever 107 to rock it on its pivot 108 in opposition to the spring 109 so as to disengage 45 the hook 113 from the keeper 114. This permits the spring 115 to exert a pull upon the short arm of the bell-crank lever 106 to move the lever 107 upwardly. The shoulder 112 on the lever 107 being previously engaged with a tooth on the adjacent disk 102 to one side of the center of the disk mounting, as indicated in dotted lines 107', Fig. 14, the upward movement of the lever 107 will cause the disk to rotate one position, 50 which is sufficiently far to cause the shoulder 112 to slide over the edge of the disk tooth. This permits the bell-crank lever 106 to continue its upward movement until an upwardly extending member 117 on the 55 outer end of the long arm of the bell-crank will come into engagement with a tooth on the disk 102 to lock it against further rotation, the lever 107 and the bell-crank 106 then assuming the third position, as shown 60 in dotted lines 107", Fig. 14.

In this manner, when any disk 102 is moved to the 10-position, the pin thereon will automatically release a lever 107 allowing the latter to move the adjacent disk one position. For example, assume the number 999, as indicated in the machine, in which instance the pin 108' on the units, tens, and hundreds disks will be in position to actuate a lever 107. If the unit disk then be moved one notch the pin thereon will operate a lever 107 to rotate the tens disk one notch, which, in turn will actuate a lever 107 to rotate the hundreds disk one notch so that the number indicated will then read 1000.

It is obvious that after writing a number 80 on this machine, it will be necessary to restore the carrying mechanism just described, to normal before writing another line of numbers. This is accomplished by means of a restoring lever 118 which extends transversely above the long arm of the bell-crank levers 106 and is supported on the outer ends of arms rigidly mounted on a revoluble shaft 119 on the standards. By 85 rotating the shaft 119 to move the restoring bar 118 downward, any number of the bell-crank levers which may be in their uppermost position may be depressed so as to cause the hook 113 on the lower ends of the lever 107 thereon to be reengaged by a 90 keeper 114.

In performing the operation of subtraction, the minuend is printed on the sheet on the platen roll and at the same time indicated on the disks 102 before the gear 67 is 100 thrown into engagement with the gear 68 to reverse the direction of rotation of the gear 62 and disks 102. The disks 102 in rotating clockwise to indicate the result or difference in subtraction operate in an opposite 105 manner to that of addition, the pins 108' then actuating the carrying levers 107 from the right-hand side.

The indicating disks 102 are returned to normal, that is, to the cipher reading position, by rotating the shaft 101 in any suitable manner. The frictional contact of the shaft 101 with the disks thereon is sufficient to cause the latter to rotate therewith.

The tension of the springs 109 is sufficient to allow the upper end of the lever 107 to act as a stop to limit the revolution of a disk 102 when the pin 108 comes in contact therewith.

A stop pin 120 on the standard 100 is 120 disposed in line with the pin 108' on the left hand disk 102 to insure its alinement on the return to normal.

Means are provided for preventing the operation of the computing mechanism when 125 it is desired to operate the digit bars without actuating the computer disks 102 and the mechanism relating thereto. This means consists of a lever 125 pivotally mounted on the frame 5 and connected to a key-bar A 130

as shown in Fig. 8 and adapted to be operated by the depression of a button on the latter in such manner as to throw a projection on one end of the lever 125 in the rear 5 of a shoulder 126 on the rack 79. The lever 125 is retained in engagement with the shoulder 126 to prevent the rearward movement of the rack 79 when the rocking lever 125 is depressed by retaining the outer end 10 of the key-bar A which is connected to the lever 125 in its lowermost position. This may be accomplished in any desired manner, but is here shown as engaged by a shoulder 127 formed on the casing 5, as indicated in dotted lines in Fig. 9. A spring 128 restores the key-bar A to normal when the latter is disengaged from the shoulder 127 and normally holds the lever 125 out 15 of engagement with the shoulder 126 on the rack 79, as shown in Fig. 8.

Means are provided for insuring the shaft 61 coming to a stop in the proper positions which means are shown in Fig. 11, and consists of a ten-toothed ratchet 129 rigidly mounted on the shaft 61, the teeth of which are engaged by a roller 130 on a lever 131, which roller is caused to bear against the ratchet 129 by means of a helical spring 132 acting on the lever 131. The tension of the spring 132 is sufficient to cause the roller 130 to enter the notches in the ratchet 129, in such manner as to cause the shaft 61 to stop when its driving power is thrown out, at that point.

From the foregoing description of my invention it will be seen that I have produced a combined typewriter and computing machine in which mechanical power is employed in operating the printing and computer mechanisms; motive power being used to restore the type-bar operating mechanism to normal in opposition to tensioned driving means, and also in restoring the computer actuating mechanism to normal in opposition to a spring which is tensioned to operate the computer. The typewriter and computer being spring actuated obviates the necessity of heavy impacts on the keys of the machine, the operator merely depressing 45 a key to release certain engaging members to admit of the motor and various tensioned elements performing the work requiring power. This admits of the machine being operated at high speed with very little effort 50 or exertion on the part of the operator, speed being further facilitated by reason of the fact that it is not necessary to await the return of a key-bar A to its normal position before depressing another key. Any number 55 of the keys may be held down at the same time; it being only necessary to depress them successively. This is permitted by reason of the type-bars being returned to normal by the spring 9 as soon as the

actuator-bar 13 is retracted, irrespective of the position of the operating arm 3.

Having thus described my invention, what I claim and desire to secure by Letters Patent is—

1. The combination in a typewriting machine having a series of type and digit bars, an actuating bar for operating the type and digit bars, a rotary motor, means by which the motor will move the actuating bar in a backward direction, spring means for moving the actuating bar in the forward direction, and key bars for causing the actuating bar to operate the type and digit bars, of a series of toothed computing disks, and means for rotating said disks controlled by the forward movement of said actuating bar.

2. In a typewriter, a computing mechanism consisting in the combination with the printing mechanism of a typewriter of a power bar with means for operating the printing mechanism by the power bar, a series of count wheels denominational arrangement in train, a key controlled selective mechanism for positioning a count wheel according to the numeral represented by the key struck, and means operated by the power bar for restoring the selective mechanism to initial position after each depression of a key.

3. In a typewriter, the combination with the printing mechanism, a power bar for operating the printing mechanism, a bank of digit key bars, a series of count wheels denominational arrangement in train, a shiftable actuating gear for said wheels, means including a single rack and pinion for rotating the gear a fraction of a revolution corresponding to the key bar depressed, spring means tending to move the rack in one direction, means controlled by the key bars to govern the movement in that direction of the rack, and means controlled by the power bar to move the rack in the opposite direction.

4. In a typewriter, the combination of a series of denominational count wheels arranged in train, a shiftable master gear engageable with said wheels, mechanism including a single rack and pinion for operating the gear, a shaft upon which the gear is splined having a reversing device, a power bar connected with the rack to move the latter in one direction, a bank of digit key bars, and means controlled by the key bars to move the rack in the opposite direction a distance corresponding to the denomination of the depressed key.

5. In a typewriting machine, the combination with a bank of digit bars and a bank of key bars for selecting same, of an actuator bar for operating the selected digit bar, a series of toothed computer disks rotatable on a shaft, a pinion keyed on a revoluble shaft,

and means for throwing said pinion into successive engagement with the computer disks.

6. In a typewriter, the combination of a series of denominational count wheels arranged in train, mechanism including a rack and pinion for operating the count wheels, a power bar connected with the rack to move the latter in one direction, a bank of digit key bars, and means controlled by the key bars to move the rack in the opposite direction a distance corresponding to the digital value of the depressed key, said last-named means including a stop bar normally disposed in the path of the rack, and a series of selector bars corresponding to and controlled by the key bars, said selector bars acting on the stop bar to release the latter and said selector bars constructed and arranged whereby on the operation of one it releases said stop and also forms a detent to the movement of the rack.

7. In a typewriter, the combination of a sliding rack with recording mechanism operated by the rack, a bank of digit key bars, a power bar operative to move the rack in one direction, spring means tending to move the rack in the opposite direction, a detent normally acting on the rack in opposition to the spring, and selector mechanism comprising a set of levers bearing at one end upon said detent each operable by the individual key bars to depress the detent and forming a stop to limit the movement of the rack and permit it to travel a distance corresponding to the digital-value of the depressed key bar.

8. In a typewriting machine, the combination of a bank of digit bars, a bank of key bars for selecting the digit bars, a spring impelled actuator bar for operating the selected digit bar, a series of computer disks corresponding in number to the digit bars, means by which the operation of a digit bar will rotate a computer disk a fraction of a revolution, means for governing the direction of rotation of the computer disk, means by which the actuator bar may operate the digit bar without operating the computer disks, and means operable by the key bars for restoring the computer disks to the initial zero position.

9. In a computing mechanism, the combination of a denominational series of count wheels rotatable in opposite directions for the processes of subtraction and multiplication, a spring actuated lever for each count wheel except the one of highest denomination, a spring actuated and balanced dog on each lever, means by which a count wheel on the completion of a full revolution in either direction will operate a respective dog to cause said dog to move a succeeding count wheel one step, and a lock on the lever car-

rying said dog engaging and temporarily limiting the further movement of the last named count wheel beyond its one step.

10. In a computing mechanism, the combination of a pair of count wheels arranged side by side each turnable in opposite directions, a spring pressed bell crank lever, a balanced dog on the lever movable in either direction, a stationary detent engageable by the dog for holding the latter and the lever against the tension of the actuating spring for the lever, and means whereby one count wheel trips said dog to release it for coupling with the other count wheel to move it with impulse by the lever.

11. In a computing mechanism, the combination of a pair of count wheels arranged side by side and turnable in either direction, a spring pressed bell crank lever, a yieldably mounted dog on the lever, a stationary detent engageable by the dog for holding the latter and the lever against the tension of the actuating spring for the lever, the dog being releasable from the detent by movement in opposite directions, means whereby one count wheel trips said dog to release it to engage the other count wheel and turn it one step by impulse of the lever, the lever engaging the count wheel moved by the dog to limit the further movement of said count wheel.

12. In a typewriting and computing machine, a computing mechanism, a spring for automatically actuating the mechanism, type-digital bars with return springs, an actuator for and common to all said bars connected to said mechanism, a spring for automatically actuating the actuator, and a motor operatively connected to said actuator for setting the same against its spring, and providing power to tension the computing mechanism spring.

13. In a typewriting and computing machine, a computing mechanism, a spring for automatically actuating the mechanism, type-digital bars with return springs, an actuator for and common to all said bars connected to said mechanism, a spring for automatically actuating the actuator, a motor operatively connected to said actuator for setting the same against its spring and providing power to tension the computing mechanism spring, coupling means interposed between said actuator and the type bars for transmitting motion from the actuator to a selected type bar, and keys for operating the couplers and determining the stroke of the computing mechanism.

14. The combination in a typewriting machine having type and digit bars, an automatic actuator common to all said bars, means for normally restraining the actuator, manually operable key-levers operative upon said means for releasing said means to per-

mit the automatic functioning of said actuator, a motor for retracting the actuator, of a set of computing disks, means for rotating said disk controlled by said actuator, 5 including a device for providing for the full stroke of the actuator but for limiting the rotation of said disks.

15. In a typewriting and computing machine, the combination of a series of digit bars, a bank of corresponding computing disks, a continuously operating power shaft, a reciprocating rack having a connection with said disks for rotating the same, a common actuator connectible with said power

shaft to receive a fixed degree of movement for operating said digit bars and reciprocating rack, and a bank of digit key levers controlling the connections between the actuator and power device and determining the degree of movement of said rack. 15 20

In testimony whereof I have hereunto set my hand in the presence of two subscribing witnesses.
